NIGHT LIGHT

Nick Shubert, 1692 Mahoning Ave., Youngstown, Ohio

Filed Feb. 18, 1959, Ser. No. 54,665

Term of patent 7 years

(Cl. D48—20)

Figure 1 is a perspective view of the night light showing my new design.

Figure 2 is an elevational view as seen from the opposite side of the night light.

Figure 3 is a top plan view of the night light.

The bottom of the night light is substantially plain. The light bulb shown in broken lines in Figure 3 is for illustrative purposes only.

The end of the night light not shown is plain.

I claim:

The ornamental design for a night light, as shown and described.
